UNITED STATES PATENT OFFICE.

WILLIAM M. GILBERT, OF NORTH WALES, PENNSYLVANIA.

DESIGN FOR A CLOTHES-PIN.

SPECIFICATION forming part of Design No. 27,245, dated June 22, 1897.

Application filed May 7, 1897. Serial No. 635,591. Term of patent 14 years.

To all whom it may concern:

Be it known that I, WILLIAM M. GILBERT, a citizen of the United States, residing at North Wales, in the county of Montgomery and State of Pennsylvania, have invented and produced a new and original Design for Clothes-Pins, of which the following is a specification, reference being had to the accompanying drawings, showing the same.

Figure 1 of the drawings is a side view of a clothes-pin showing my new design for the same, and Fig. 2 is an end view.

As shown in the drawings, the leading or material feature of my design consists of a cylindrical pin with tapered and symmetrical

ends A and B of a circular cross-section, each made alike with a terminal bulb F. A lateral notch or cut D is formed in the side of the clothes-pin near one end and extends in the shape of a slot E up to a point near the 20 taper of the other end. Inside the slot E on the unbroken side of the clothes-pin there is a notch or transverse groove C.

What I claim is—

The design for a clothes-pin as herein shown 25 and described.

WILLIAM M. GILBERT.
